UNITED STATES PATENT OFFICE.

RODERICK KRAATZ, OF CARBONDALE, ILLINOIS.

FORGE.

No. 841,159.

Specification of Letters Patent.

Patented Jan. 15, 1907.

Application filed October 9, 1906, Serial No. 338,161.

To all whom it may concern:

Be it known that I, RODERICK KRAATZ, a citizen of the United States, residing at Carbondale, in the county of Jackson and State 5 of Illinois, have invented certain new and useful Improvements in Forges; and I do hereby declare the following to be a full, clear, and exact description of the invention, such as will enable others skilled in the art to 10 to which it appertains to make and use the same, reference being had to the accompanying drawings, and to the figures of reference marked thereon, which form a part of this specification.

15 This invention relates to a forge, and particularly to a structure adapted to be adjusted relative to the work to be heated.

The invention has for an object to provide a novel and improved construction by which 20 the forge may be vertically adjusted upon its supporting-standards and retained at such adjustment, together with means at the front of the forge by which structures adjacent to the part to be heated may be protected from 25 the blasts.

Other and further objects and advantages of the invention will be hereinafter set forth and the novel features thereof defined by the appended claims.

30 In the drawings, Figure 1 is a side elevation of the invention applied to a truck or car. Fig. 2 is a plan view thereof. Fig. 3 is a vertical sectional view on line 3 3 of Fig. 2, and Fig. 4 is a detail sectional view showing a 35 latch.

Like numerals of reference designate like parts in the several figures of the drawings.

The invention is adapted for any application of a forge, but particularly for adjustment relative to a car or truck—such, for instance, as shown in Fig. 1. The frame 1 of the truck is provided with a bearing-box 2 and a wheel 3 to travel on the rail 4, mounted upon a tie 5 or other suitable support. The 45 upper portion of this car is provided with an arm 6, having an extended end 7, which in the practical use of cars of this structure frequently becomes bent or distorted, and in the instance where such cars or trucks are used 50 in connection with kilns or chambers for treating the material carried thereby this end portion must be bent back to its original con-

formation in order to permit the continued use of the car or truck.

The forge when used in connection with 55 work of the character just described is mounted upon a fixed support adjacent thereto by means of standards 8, which support a cross-bar 9, having vertically-extending posts 10 thereon. These posts are adapt- 60 ed to travel in sleeves 11, formed at the corners of the forge-box 12, as shown in Fig. 2, so as to guide the sliding movement of said box. The raising of the box is accomplished by means of the rock-shaft 13, mounted in 65 bearings 14, depending from the frame, such rock-shaft being connected by the crank-arm 15 and the link 16 with the end wall 17 of the forge-box. This link is protected against injury by a keeper 18, mounted on the stand- 70 ards 8. The extended end 19 of this keeper is provided with ratchet-teeth 20, which co- 75 operate with a pawl 21, pivotally mounted on the operating-handle 22, carried by the end of the rock-shaft 13. The connecting- 75 link 16 is duplicated at the opposite end of the box, so that an even raising movement is secured.

As shown in Fig. 2, the forge-box is di- 80 vided into several compartments—that is, a central compartment 23, having a blast-box 24 therein, and the connecting air-pipe 25, extending thereto. This blast-box is pro- 85 vided with the usual shaker, having the rod 26 extended therefrom to the rear of the forge. At the opposite end of the box fuel- 90 compartments 27 are formed, the partition thereof comprising parallel walls 28, between which a sliding gate 29 is mounted, this gate being connected by a link 30 with a shifting 90 lever 31 thereof, which is pivotally mounted at its lower end upon the lug 32 and pro- 95 vided with a handle 33 at its upper portion. By this construction the coal may be readily fed to the forge-chamber or the fuel-com- 95 partment cut off therefrom, as found desir- able. The front of the forge-box is provided with pivoted doors 34, each of which is of angular construction and mounted on the end wall 17 of the forge-box by means of the pivot 35, while the free edge of these doors is provided with a pivoted latch 36 (shown clearly in Fig. 4 of the drawings) and adapted to embrace or engage the work and hold the 100

doors in position relative thereto, so as to prevent injury to any adjacent portion of the structure being heated. The forge-blast may be driven in any desired manner. For instance, the pipe 25 is extended to the fan-box 37, as shown in Fig. 2, and the blast-fan therein is provided with a pulley 38 upon its shaft, over which the belt 39 extends from a driving-pulley 40. This driving-pulley carries upon its shaft a pinion 41, which meshes with a gear 42 on the shaft 43, the extended end of which is formed with a hand-crank 44 of the usual character, all of these parts being supported in an extended frame 45 at the rear of the forge-box, while the parts of the driving mechanism are protected from the heat by means of a shield 46, extending upward at the rear of the forge.

In the operation of the invention the forge is adapted to be adjusted to the side of the car or other object to be heated, and the portion to be forged—for instance, the extended arm—is adjusted so as to be in contact with the fire and thoroughly heated thereby, so that it may be bent to its proper position without the necessity of disassembling the parts of the car. This is particularly useful in cars or trucks used in the treatment of railway-ties, where the supporting-arm thereon being effected by the acid used in such treatment becomes badly bent or distorted, so that it will not enter the compartment used in treating the material, and the present invention is adapted to adjust the forge to such a part for heating the same preparatory to restoring it to the original position. The angled doors inclosing the front of the forge prevent the loss of fuel therefrom and also protect the portion of the car or truck from heat which is adjacent to the arm, and the hook upon these doors is adapted to engage the arms and retain them in proper position. The vertical adjustment of the forge-box which is to be raised to the desired elevation brings the fire in proper relation to the work to be heated. In case it be desired to mount the forge in a fixed position and to bring the cars over the same the gates at the opposite fuel-boxes may be drawn back and the angled doors swung open, so as to allow a free passage for the structure to be heated directly above the fire-box.

What I claim is—

1. In a forge, a base-frame provided with guide-posts, a forge-box slidably mounted upon said posts, a lever carried by the frame, and a connection therefrom to the forge-box, as set forth.

2. In a forge, a base-frame provided with guide-posts, a forge-box slidably mounted upon said posts, a lever carried by the frame, a connection therefrom to the forge-box, an extended frame at the rear of the forge-box,

and a blower and driving connection carried by said frame and adjustable with said box, as set forth.

3. In a forge, a base-frame provided with guide-posts, a forge-box slidably mounted upon said posts, a lever carried by the frame, a connection therefrom to the forge-box, an extended frame at the rear of the forge-box, a blower and driving connection carried by said frame and adjustable with said box, fuel-chambers at the opposite ends of the forge-box, and a sliding gate between said chambers and the forge, as set forth.

4. In a forge, a base-frame provided with guide-posts, a forge-box slidably mounted upon said posts, a lever carried by the frame, a connection therefrom to the forge-box, an extended frame at the rear of the forge-box, a blower and driving connection carried by said frame and adjustable with said box, fuel-chambers at the opposite ends of the forge-box, a sliding gate between said chambers and the forge, and angular doors pivotally mounted upon the opposite ends of the forge-box and adapted to partially inclose the front thereof, as set forth.

5. In a forge, a base-frame provided with posts thereon, a forge-box slidably mounted upon said posts, a rock-shaft carried by said frame and provided with a crank-arm therefrom at each end, a link extending from said arms to the ends of the forge-box, an operating-lever carried by said shaft and provided with a retaining-pawl, and a rack-bar mounted upon said frame in the path of travel of said pawl, as set forth.

6. In a forge, a base-frame provided with posts thereon, a forge-box slidably mounted upon said posts, a rock-shaft carried by said frame and provided with a crank-arm therefrom at each end, a link extending from said arms to the ends of the forge-box, an operating-lever carried by said shaft and provided with a retaining-pawl, a rack-bar mounted upon said frame in the path of travel of said pawl, a keeper embracing the link connections at the ends of the forge-box, and angular doors pivotally mounted on the ends of said box and adapted to partially inclose the front thereof, as set forth.

7. In a forge, a base-frame provided with posts thereon, a forge-box slidably mounted upon said posts, a rock-shaft carried by said frame and provided with a crank-arm therefrom at each end, a link extending from said arms to the ends of the forge-box, an operating-lever carried by said shaft and provided with a retaining-pawl, a rack-bar mounted upon said frame in the path of travel of said pawl, a keeper embracing the link connections at the ends of the forge-box, angular doors pivotally mounted on the ends of said box and adapted to partially inclose the front

thereof, and pivoted hooks carried by the free edges of said doors, as set forth.

8. In a forge, a box provided at opposite ends with fuel-compartments by means of a partition-plate extending for part of the width thereof, a sliding gate disposed parallel to each of said partition-plates and adapted to engage the front wall of the box, an oper-

ating-lever for said gate, and a link connection between the gate and lever, as set forth. 10

In testimony whereof I hereunto affix my signature in the presence of two witnesses.

RODERICK KRAATZ.
